UNITED STATES PATENT OFFICE.

HART IRVING SEELY, OF WAVERLY, NEW YORK.

GLOVE.

1,358,791.

Specification of Letters Patent. Patented Nov. 16, 1920.

Application filed September 16, 1919. Serial No. 324,131.

To all whom it may concern:

Be it known that I, HART IRVING SEELY, a citizen of the United States, and a resident of Waverly, in the county of Tioga and State of New York, have invented a new and Improved Glove, of which the following is a full, clear, and exact description.

It is a well-known fact that gloves, and more particularly heavy workmen's gloves, usually made of leather or a similar material, are inclined to break along the lines of joining, which usually consists of stitching with cotton thread at the parts where they are subjected to the greatest strain and wear.

The joint which undoubtedly is subjected to the heaviest strain is the connection between the palm and thumb blanks; and it quite often occurs, as is well known, that an otherwise serviceable glove must be discarded, or repaired in an inefficient manner, due to the fact that this seam or joint has an opening caused by strains and wear thereon.

With a view of overcoming this defect, I have provided a connection which is to be employed in the construction of gloves more particularly intended for engineers, firemen, etc., which serves to join the palm and thumb blanks together in such a manner that this connection will hold these two parts in proper relationship one with respect to the other until the glove has outlived its usefulness.

Further, it might be found that the means employed in joining the palm and thumb blanks would have a tendency to become dislodged unless securely fastened in place, and with this in mind I have constructed a glove which may have said securing means an integral part of either the thumb or palm blank.

Reference is had to the attached sheet of drawings which illustrates one practical embodiment of my invention, and in which— Figure 1 is a bottom view of a glove showing applied thereto the construction utilized to produce the aforementioned result;

Fig. 2 is an enlarged sectional view taken along line 2—2 of Fig. 1;

Fig. 3 is an enlarged sectional view taken along line 3—3 of the same figure; and

Fig. 4 is an enlarged plan view of a thumb blank constructed in accordance with my invention.

In all of these views like reference numerals designate similar parts, and the reference numeral 1 indicates a glove which may be conveniently provided with a gauntlet, such as 2, of any desired construction. 60

Due to grasping of tools, levers and articles which are sometimes very hot, the connection between the palm 3 and thumb 4 of stitching 5 is, as aforesaid, very often broken. To remove this defect I perforate 65 the thumb blank adjacent its palm edge, as indicated by the reference numerals 6, and provide the under- or overlying portions of the palm 3 with corresponding perforations.

To this end I provide a lacer 7, which 70 may be threaded through the perforations 6 of both the palm and thumb, in addition to the rows of stitching 5, and preferably, as clearly shown in Fig. 1, between the same. It will readily be appreciated that by thus 75 providing a connection of this type between the palm and thumb of a glove it will be virtually impossible for the one to become separated with respect to the other before the glove has outlived its usefulness. 80

The lacer 7, with a view of economy and simplicity, is conveniently made of an integral part of the thumb 4, and may readily be formed, as clearly shown in Fig. 4, by slitting the thumb blank between that edge 85 adjacent to which the perforations 6 are formed, and the perforations of such slit preferably extending parallel to such edge whereby to form the lacer 7. The slit terminates at a point substantially in line with 90 said perforations 6 so that one end of the lacer may be conveniently retained in fixed position with respect to the thumb blank 4 indicated by the reference numeral 8, cutting from the body of the same but permitting a connection to remain between the upper end of the lacer and the thumb, as indicated by the reference numeral 8. As shown in Fig. 2, stitching 5 may serve to retain the lower end of the lacer in fixed 100 position.

From the above it will be appreciated that I have constructed a glove which is unusually strong and which may be cut in such a manner as to entail virtually no additional 105 expense for the reinforcement provided. It will further be understood that by the aforementioned construction I have invented a method of joining the palm and thumb blanks of a glove in such a manner that the 110

glove itself will be practically heat-, fire-, acid-, and water-proof, in view of the fact that the leather lace is capable of withstanding any reasonable amount of wear 5 incident to contact with these elements, which would not be the case where a thread alone is used to join these two portions, in view of the fact that any exceptional amount of heat, or of any of the above elements 10 named, will act extremely detrimental to thread, resulting in a breaking of the same and the parting of the thumb and palm blanks.

As will be readily understood, any number 15 of modifications in the arrangement of my lacer and its method of attachment may

readily be resorted to without in the least departing from the scope of my invention.

Having thus described my invention, I desire to claim and secure by Letters Pat- 20 ent:

A glove including overlapping thumb and palm portions having a line of registering perforations, one of said parts having a slit 25 adjacent its edge extending to a point adjacent one end of the line of perforations, said strip formed by the slit, forming a lacer adapted to be threaded through the registering perforations and being secured at its free end.

HART IRVING SEELY.
